ELECTRICAL TREATING APPARATUS, ESPECIALLY FOR STERILIZATION

Franklin S. Smith, New Haven, Conn.

Original application August 2, 1932, Serial No. 627,291. Divided and this application October 8, 1934, Serial No. 747,440

24 Claims. (Cl. 21—102)

This invention relates to apparatus which is especially adapted for the electrical sterilization of products, particularly for the destruction of insect life in food and other products and this application is a division of my application, Serial No. 627,291, filed August 2, 1932, now patent No. 1,975,805, issued Oct. 9, 1934.

One of the objects of this invention is to provide a thoroughly practical and dependable electrode construction and driving means therefor, adapted to be subjected to high voltage and to produce a corona-like discharge in the treatment zone through which the products to be sterilized are passed. Another object is to provide a construction of the above-mentioned character that is well adapted to meet the various and varying conditions met with in practical use. Another object is to provide a simple and practical mounting for such an electrode structure as well as to provide a dependable and reliable circuit or circuit connections therefor. Other objects will be in part obvious or in part pointed out hereinafter.

The invention accordingly consists in the features of construction, combinations of elements, arrangements of parts as will be exemplified in the structure to be hereinafter described and the scope of the application of which will be indicated in the following claims.

In the accompanying drawings, in which is shown one of the various possible embodiments of my invention,

Figure 1 is a fragmentary front elevation of the complete sterilizing apparatus, certain parts being, however, shown diagrammatically and other parts being shown in central vertical section;

Figure 2 is a vertical central sectional view, on an enlarged scale, showing one of the electrode structures and driving motor and mounting therefor;

Figure 3 is a plan view, on an enlarged scale, substantially as seen along the line 3—3 of Figure 1;

Figure 4 is a detached fragmentary vertical sectional view through a portion of the electrode structure, showing also one electrode member in front elevation;

Figure 5 is a horizontal sectional view on an enlarged scale as seen along the line 5—5 of Figure 4;

Figure 6 is a horizontal sectional view on an enlarged scale as seen along the line 6—6 of Figure 4;

Figure 7 is an isometric view of a piece of insulating tubing showing the manner of producing

a portion of the electrode supporting structure therefrom;

Figure 8 is a detached fragmentary plan view of the rotor and stator construction embodied in the electrode structure of Figure 2, and

Figure 9 is a detached fragmentary front elevation of the rotor of Figure 8.

Similar reference characters refer to similar parts throughout the several views in the drawings.

Referring first to Figure 1, in which I have shown a side elevation of the complete apparatus of my above-mentioned parent application, omitting, however, certain parts and showing certain other parts diagrammatically and to which parent application reference may be made for a detailed description of the diagrammatically-indicated and omitted parts, I have indicated at 10 the frame of the machine provided at its ends with upstanding pairs of stands 24—25 respectively supporting a driving drum 27 and an idler or supporting drum 29 about which extends a conveyor belt 28 made of any suitable non-conductive material and provided with a belt-supporting structure which may comprise insulating side beams 64—65 (see also Figure 3) supporting a flat elongated rectangular sheet of insulating material 62, preferably made of "dilecto" or laminated "bakelite" which is in intimate contact with the lower surface of the upper side of conveyor belt 28 and in direct supporting relation thereto; this sheet of insulating material 62 may, as disclosed in my parent application, be interrupted throughout the two treatment zones in order to receive, also in belt-supporting relation, plates of "pyrex" glass or fused quartz, one for each treatment zone, and in Figures 1 and 3 two such plates 67 and 68 are shown.

Accordingly, the conveyor belt 28, when driven to move the upper side thereof from the right toward the left, as viewed in Figure 1, may support and move the goods to be sterilized, illustratively packaged goods, such as packaged cereals, flour, or the like, indicated at C in Figure 3, for electrical action thereon, the details of which action are described and analyzed in my above-mentioned parent application.

As the packages of product to be treated are moved along the conveyor from the receiving end to the discharge end of the apparatus, they pass beneath the electrodes 91 and 92 and through treatment zones associated therewith, as will appear more fully hereinafter.

The electrodes, illustratively two, 91 and 92 are preferably supported in a common plane substan-

tially parallel to the upper conveying surface of the belt 28 in substantial alignment above the center line of the belt. Electrodes 91 and 92 are maintained in spaced relation above conveyor belt 28 by metallic brackets 93 and 94, respectively, which in turn are suitably supported in a manner more fully described hereinafter.

Each electrode 91 and 92 is preferably provided with upstanding stem portions 95 and 96, respectively, which are received within suitable hole portions 93a and 94a, respectively, provided in brackets 93 and 94 and permanent fastening therein is preferably effected by wedge-shaped pins 97 and 98 passing through suitable holes provided in bracket 93, stem 95, and bracket 94 and stem 96, respectively.

For reasons as will appear more fully hereinafter, the brackets 93 and 94 are preferably mounted on a horizontal frame forming an acute angle with the common plane of the electrodes 91 and 92.

In order that the electrodes 91 and 92 may be firmly and rigidly supported by the brackets 93 and 94, respectively, the brackets are preferably of unsymmetrical construction, the one, 94, being of an increased length since it extends across the wider portion of the above-mentioned angle between planes. Similarly, the stem portion 96 of the electrode 92 associated with the longer bracket 94 is preferably of an increased length to give added rigidity to the connection with the longer bracket.

Electrodes 91 and 92 are preferably of analogous construction for reasons of manufacturing economy so that a detailed discussion of electrodes 92 only will be given.

Referring now more particularly to Figure 2, there is shown at 99 an inverted dish-shaped housing preferably of cast aluminum, having high electrical conductivity, with a central humped body portion 99a and a flat rim portion 99b.

Fastened to the inverted dish-shaped housing 99, by suitable screws 100, is a dish-shaped housing portion 101 also preferably of cast aluminum having a central downwardly extending body portion 101a and a flat outwardly extending rim portion 101b.

The outer rim portion 101b of the lower portion of the housing preferably includes two concentric thickened ring portions 101c and 101d, each of which is provided with spaced hole portions 101e (see also Figure 3) in an alternate or staggered relation which are adapted to receive electrode members 102. Between concentric thickened ring portions 101c and 101d of the rim 101b is a relatively thin interconnecting section 101f, and similarly between the inner thickened ring portion 101d and a central downwardly extending body portion 101a is a relatively thin interconnecting section 101g; this construction makes for a saving in material yet permits adequate mountings for the electrode members 102.

The various electrode members 102 are preferably of identical construction comprising (see Figure 4) a main cylindrical body portion 102a, an upper flat circular head portion 102b, and a lower conical sharp tip portion 102c. The various electrode members are preferably made of nickel steel tubing worked into the form indicated and highly polished, particularly adjacent the extreme tip portions thereof, to give smooth unbroken surfaces free from irregularities and small projections; the advantages to be derived from this construction will appear more fully hereinafter.

The various hole portions 101e arranged in two concentric rings about the concentric ring portions 101c and 101d, respectively, of the lower portion of the housing, are preferably inclined at a common angle of 50° or 60° with respect to a plane normal to the axis of the electrode; the center lines of the holes and consequently the center lines of the various electrode members individually associated with the holes lie in planes substantially tangent to either of the two concentric ring portions of the lower electrode housing. Thus, the extreme tip portions 102d of the various electrode members lie along two concentric circles and preferably in a common plane.

Electrode 92 is preferably rotated, in a manner to be more fully described hereinafter, in such a direction that the upper head portions of the electrode members are leading with the extreme tip portions trailing; for the electrode 92 the rotation, as seen looking down on the electrode (see Figure 3) is in a counter-clockwise direction. An individual electrode member (see Figure 4) illustratively moves in a direction from the left to right with its upper portion leading and with its lower tip portion trailing. A horizontal section taken through the main portion of the electrode member (see Figure 5) is elliptical in form and through the tip portion substantially egg-shaped in form (see Figure 6) thus giving a substantially stream-line construction to the slanting electrode member which effects a minimum disturbance of the ambient air, the desirability of which will appear more fully hereinafter in considering certain electrical actions of the apparatus, as the electrode is rapidly rotated as indicated above.

While various numbers of electrode members may be used in the construction of an electrode depending upon the diameter of the rotatable electrode, the number of rings of concentric electrode members, the size of electrode members, and the spacing between them, I conveniently employ electrode members spaced from each other in a circle so that their projected lengths are approximately equal to the distance between these projections.

The diameters of the illustratively two concentric circles in which the electrode members are arrayed are preferably such that the projection of the outer circle falls beyond both edges of the conveyor belt 28 (see Figure 3), while the projection of the inner circle overlaps and just falls outside of the path of travel of the packaged product or articles to be treated; the diameter of the larger circle is preferably slightly greater than the width of conveyor belt, while that of the smaller circle is slightly less.

For a conveyor belt of about 14 inches in width, the outer ring of electrode members is about 16 inches in diameter including illustratively 9 electrode members of 4 inches in length spaced 40° apart, while the inner ring of electrode members is about 10½ inches in diameter including illustratively 9 electrode members 4 inches long spaced 40° apart and alternating with the electrode members of the outer ring.

The various highly polished, illustratively nickel-steel, electrode members are removably positioned in the various above-mentioned holes provided in lower portion 101b of the electrode housing and so held that their various flat head portions 102b are snugly received within countersunk portions 101h (see Figures 3, 2 and 4), by contact with the lower surface of the flat rim portion 99b of the upper portion of the electrode.

housing; upper and lower portions of the housing being held in assembled relation by screws 100.

With this construction the various electrode members may be removed and replaced by other electrode members of the same kind or by electrode members of a different kind, longer or shorter, with the extreme tip portion sharper or more blunt, or of a different material, all with a minimum disturbance of the other portions of the apparatus. Furthermore, such a construction gives a good firm support to the various electrode members which in addition is well adapted to transfer the heat produced at the tip portions of the electrode members to the body of the electrode where it is readily dissipated; the construction is also of high electrical conductivity and light in weight, all of which make for a high operating efficiency and an economy in manufacture.

The electrode housing 99 with its associated electrode members 102 is rotatably mounted, as indicated above, on the shaft 96, the upstanding or stem end of which, as above-mentioned, is suitably secured to bracket 94.

Shaft 96 is formed with a central enlarged portion 96^a and with an adjacent narrow portion 96^b which snugly receives the inner race 103^a of the ball bearing assembly 103.

The lower end of the inner race 103^a of the ball bearing assembly firmly abuts a shoulder portion 96^c of the shaft between the expanded and more reduced sections 96^a and 96^b, respectively, and is held in firm abutting relation by the retaining ring 104 threadedly engaging the shaft as at 96^d; thus, the ball bearing assembly 103 is securely mounted on the shaft 96.

The upper portion 99^a of the electrode housing is provided with a central hole 99^c in thick wall construction 99^e adapted to snugly receive the outer race 103^b of the ball bearing assembly. The upper part of the hole portion provided in the upper part of the electrode housing is of a similar diameter so as to provide a shoulder which rests upon the upper end of the outer race 103^b of the ball bearing assembly. Thus, the electrode housing 99-101 is rotatably mounted on the shaft 96 with its weight sustained by the ball bearing assembly 103.

To give a dirt-tight, dust-tight and grease-tight fitting between the rotatable housing 99-101 and the fixed shaft 96, the upper part of the upper portion 99 of the electrode housing is recessed as at 99^d and fitted with the felt washer 105, the inner edge of which lightly contacts the outer periphery of retaining ring 104. The fitting is completed by dust plate 106 in the form of a flat ring which is received within the recessed portion 99^d of the upper portion of the housing and rests upon the felt washer 105; the plate and washer are secured to the housing by suitable screws 107. Dust plate 106 is preferably so mounted on the rotatable electrode housing as to clear fixed shaft 96 and its associated retaining ring or nut 104 to allow free rotation of the electrode.

To assure an axial rotation of the electrode 92 about the supporting shaft 96 and central part of the lower portion 91, the electrode housing is recessed as at 101^e and snugly receives the outer race portion 108^a of the ball bearing assembly 108, the inner race 108^b of which is pressed onto a reduced end section 96^e of the shaft. Thus, electrode housing 99-101 with its associated electrode members 102 is axially supported on

shaft 96 and is adapted to be rotated about its central axis with minimum frictional resistance in the bearings and minimum windage impedance (due to the effective stream-line construction of the various electrode members).

Driving energy for rotating the electrode housing 99-101 is preferably supplied by a single phase alternating current induction motor generally shown at 109, rated illustratively 220-volt, 6-pole, 60-cycle with a synchronous speed of 1200 R. P. M., preferably including a stationary field 110 mounted on shaft 96 and a rotating armature 111 associated therewith mounted on housing 99-101.

The field 110 preferably includes a laminated iron core 112 illustratively comprising a stack of individual circular disks of suitable iron 112^a and circular end plates 112^b of an appreciably thicker iron. The core is provided with a central hole portion 112^c which receives a reduced portion 96^f of the shaft; the core is pressed onto the shaft prior to the assembly of the electrode until the upper end plate 112^b abuts a shoulder portion 96^c of the shaft after which the end of the reduced section 96^f is mushroomed as at 96^g to press against the lower end plate 112^b and holds the laminated core in a compact assembled relation on the shaft.

The outer periphery of the core 112 is slotted as at 112^x and wound with the illustratively single phase 6-pole winding 113, in the manner apparent from Figure 2 and as is better indicated in Figure 8, diagrammatically. Its slotted periphery may carry shading coils S (see Figure 9) for better self-starting characteristics.

One end 113^a of the winding is brought out and grounded to the core as at 112^d, while the other end 113^b is taken up through a channel portion 96ⁱ provided in the supporting shaft 96 where it is suitably connected to conductor 114 associated with bracket 94.

Concentrically spaced about the field 110 and adjacent the outer periphery of core 112 is a ring-shaped laminated armature core 111. Armature 111 is tightly received within recessed portions of the upper and lower portions of the electrode housing with the upper and lower edges adjacent the outer periphery abutting the upper and lower portions of the electrode housing. Thus, the induction motor armature is securely fastened to the electrode housing with its core properly aligned with that of its associated field and with a proper uniform air-gap intervening.

The armature 111 preferably includes a squirrel-cage induction winding, illustratively of the copper bar and brazed end-ring type. Such an armature winding is per se known; it is diagrammatically indicated in Figure 8 at 111^a.

It may at this point be noted that induction motor 109 is received within electrode housing 99-101 allowing a suitable air space between the field windings and the nearby walls of the electrode housing. The relatively thin walled sections of the upper and lower portions of the electrode housing rapidly transfer the heat produced in the motor core and windings (and partially given up to the air enclosed within the housing) to the outer surface of the electrode housing where it is rapidly conducted away or dissipated by the ambient air through which the electrode housing rotates upon energization of the induction motor 109, in a manner more particularly described hereinafter, illustratively by way of conductor 114 and the metallic bracket 94, shaft 96 and field core 112.

Mechanical driving energy is imparted to housing 99-101 and the associated electrode members 102 causing the latter to whirl along their prescribed circular paths in a counter-clockwise direction, as above-mentioned, at a speed of approximately 4500 feet per minute for the outer ring of electrode members, and 3000 feet per minute for the inner ring for the dimensions illustratively given above.

10 Electrode 91, as above-mentioned, is analogous in construction to electrode 92 with these differences, however; the induction motor associated with electrode 91 drives the latter in a clockwise direction and accordingly the electrode members 115 associated with this electrode are slanted in the opposite direction to those associated with the oppositely rotating electrode 92, with their extreme tip portions in a trailing position, in order to realize the stream-line effects mentioned 20 above in the consideration of the action of electrode 92.

Electrodes 91 and 92 are rotated in opposite directions with the extreme tip portions of their respective electrode members whirling in, preferably, a common plane spaced above and substantially parallel to the upper conveying surface of the belt 28. These electrodes are adapted to be maintained at a high electrical potential, illustratively 150,000 volts with respect to ground, 30 the manner and purpose of which will appear more fully hereinafter.

In the upper electrode means, electrodes 91 and 92 are maintained in spaced relation above the conveyor belt 28 in the manner indicated by 35 the electrode supporting structure generally shown at 116 (see Figure 1) which preferably includes an insulating framework 117 which is supported by metallic brackets 118 and 119.

Insulating support 117 (see Figure 7) is preferably cut from a large tubular piece of insulating material, such as "dilecto" or laminated "bakelite", having appreciable mechanical strength in addition to its high electrical insulation characteristics in the form indicated. From 45 a single short length of tubing, two such insulating supports 117 and 120 may be conveniently cut having ring portions 117^a and 120^a, respectively, and loop portions 117^b and 117^c and 120^b and 120^c, respectively, located on diametrically opposite sides of the respective ring portions 117^a and 120^a. Thus, two individual insulating supporting members are obtained from a minimum length of insulating tubing with a consequent saving in material and a reduction in the 55 cost of manufacture.

Referring now back to Figure 1, the insulating supporting member 117 is preferably mounted symmetrically about a vertical axis with its ring portion 117^a lowermost and substantially horizontal about which are mounted, at diametrically opposite points, metallic brackets 93 and 94.

Brackets 93 and 94 (see Figure 3) are preferably provided with convex curved upper portions 93^b and 94^b, respectively, which are adapted 65 to contact the inner curved surface of the ring portion 117^a of the insulating support. Brackets 93 and 94 are further provided with over-hanging lip portions 93^c and 94^c (see Figure 1) which 70 squarely rest upon the upper horizontal edge of the ring portion 117^a of the insulating support which thus sustains a good portion of the weight of the electrodes and furthermore prevents displacement of the electrodes and metallic brackets 75 about a horizontal axis; the brackets are fas-

tened to the insulating support by suitable screws 121.

To prevent bending, twisting or warping of the lower horizontal ring portion 117^a of the insulating support, there are provided a pair of parallel 5 tubular conducting compression members 122 and 123 (see Figure 3), the ends of which are snugly received within suitable holes provided in brackets 93 and 94.

Holes are provided at 93^d and 94^d to receive 10 opposite ends of the conducting tube 122 in brackets 93 and 94, respectively, and similarly holes are provided at 93^e and 94^e to receive opposite ends of the tubular member 123 in the respective brackets 93 and 94. 15

The upstanding loop portions 117^b and 117^c of the insulating support are secured to metallic brackets 118 and 119, as mentioned above, the lower edges of the extreme upper portion of the loops 117^b and 117^c resting on toes 118^a and 119^a, 20 respectively, preferably made integral with the respective brackets 118 and 119; insulating supports and brackets are preferably bolted together to give a rigid and secure fastening well adapted to withstand twisting or turning about the horizontal axis as a result of lateral stresses accidentally applied to either the electrode means, the electrodes or their supports.

Brackets 118 and 119 are provided with offset threaded upper portions 118^b and 119^b, respectively, which are slightly inclined to the vertical by an amount equivalent to the incline of the conveyor, or in effect substantially perpendicular to the upper conveying surface of the conveyor belt 28. To give a free and unencumbered 25 mounting for the electrode supporting structure, brackets 118 and 119 are offset outwardly, the one 118 being offset toward the left, as seen in Figure 1, while the other, 119, is offset toward the right where they respectively engage parallel 40 threaded shafts or elevation screws 124 and 125 rotatably mounted in C-brackets 126 and 127, respectively, which in turn are illustratively welded to the upper and lower horizontal iron frame sections 22^a-18^a and 22^b-18^b, respectively. 45

C-brackets 126 and 127 are preferably so constructed that elevation screws 124 and 125, respectively, journaled or rotatably mounted therein are maintained perpendicular to and in substantial alignment with the upper part of the conveyor belt 28 and consequently in substantial 50 parallel relation with the axial mountings of electrodes 91 and 92.

Bevel gears 128-129 are controlled by a hand-wheel which is geared, through suitable gearing (not shown) to the two bevel gears 128-129 in order thereby to control the raising and lowering of the electrode structures.

It may at this point be noted that as the electrode members are raised or lowered into positions more remote from or more adjacent to the conveyor, the motion is purely translatory in a direction perpendicular to the upper conveying surface of the belt; the raising or lowering of the electrodes is effected without changing their 60 positions either longitudinally or transversely of the conveyor. Some of the peculiar advantages derived from this construction are more fully dealt with in my above-mentioned parent application.

To give a firm and rigid support for the electrodes and at the same time to maintain them at their high electrical potentials, all without undue over-all size and weight of insulating material, the support 117 is cut in the form and 70 75

manner described above and illustrated in Figure 7 to give a long electrical leakage path from the high potential electrodes to the grounded brackets.

5 Thus, a relatively long leakage path is provided for a desired height and width of insulating support, or for a desired length of insulating material calculated to withstand the high potentials employed at a maximum permissible surface leakage, a support of minimum over-all size and weight is achieved with a consequent saving in material and economy in manufacture.

10 Cooperating with the electrodes 91 and 92 of the upper electrode means and spaced immediately beneath the upper part of conveyor belt 28 and the insulating sheeting 62 of the conveyor belt supporting structure 57 (Figure 1) are arranged cooperating electrodes. The lower electrodes are preferably in the form of two right 15 cylinders 141 and 142 substantially coaxial with the electrodes 91 and 92, respectively. A suitable number of preferably identical electronic conduction devices 143 serve as electrode members to concentrate the discharge. The extreme outer 20 side diameters of the cylinders 141 and 142 of electronic conduction devices are preferably equal to or slightly less than the diameters of the circles traced by the extreme tip portions of the outer rings of electrode members 115 and 102, 25 respectively, as they are whirled above the conveyor (see also Figure 2), while the inner diameter of the cylinders or electronic conduction devices (as determined by the extreme diameters above-mentioned less twice the cross-sectional 30 diameter of the individual electronic devices comprising the cylinders) are substantially equal to or greater than the circular paths traced by the extreme tip portions of the inner rings of electrode members 115 and 102 on rotation of 35 electrodes 91 and 92, respectively.

40 Preferably, the electronic conduction devices 143 are in the form of elongated cylindrical tubes of diameters substantially equal to the distance between the inner and outer rings of electrode members 115 and 102, and of such length that they are adapted to be conveniently received 45 within the space between upper and lower sides of belt 28; illustratively the length is five or six times the diameter.

50 The various electronic conduction devices 143 are maintained in cylindrical groups 141 and 142 spaced from electrodes 91 and 92 respectively, as indicated above, by suitable racks 144 and 145 and their associated supporting yokes 146 and 55 147, respectively, preferably bolted to the side wall portions 64 and 65 of the conveyor belt supporting framework (see Figure 3).

55 These cylindrical groups 141 and 142 are respectively rotated about generally vertical axes, 60 but axes which are, more specifically, normal to the plane of the belt 28. The axes, therefore, are respectively in line with the path of movement of the electrode structures 91-92 when the latter are adjusted by manipulation of the hand- 65 wheel and respectively substantially coincident with the axes of the electrodes 91-92. As for the details of the mounting and driving of these groups 141 and 142 of electronic conduction devices 143, reference is to be made to my above-mentioned parent application.

70 Coacting with the metallic racks or bases 144-145 is a condenser plate 174 (Figure 1) positioned and insulating supported, as described in my above-mentioned application, as by the insulating beam 178 and electrically connected to

75 the racks 144-145 which in turn are electrically connected to the electrodes of the electronic conduction devices 143, all as described in my above-mentioned application. Plate 174 is spaced from the rear vertical metallic wall of the housing 10 5 and forms therewith an air condenser, the metallic wall being in connection through the frame and related parts with the grounded side 200 (Figure 1) of the high voltage winding 201 of a high frequency transformer whose primary winding 202 is connected to a suitable source 203 of high frequency current on the order of 640 cycles per second. The other terminal of the high voltage winding 201 is carried as by conductor 204 down through the high voltage insulating terminal 205 where it is connected by a suitable conductor 206 to a cross-supporting tube 122, thus impressing upon the electrodes 91 and 92 the high voltage high frequency energy, with actions and coactions as fully described in my co-pending application, conduction devices 141 and 142 being driven at a relatively low speed and in opposite directions by the crossed insulating belt 169 driven from the motor 168 supported as by standard 24. 20 25

Within the transformer casing 206 (Figure 1) is a low voltage transformer whose primary winding 207 receives energy from a source 208, such as a 110 or 220-volt power circuit and whose secondary winding 209 is insulated from the primary 30 winding 207 for the high voltage of the transformer winding 201, having one terminal connected by conductor 210 to conductor 204 and through the latter to the one or grounded side of the windings 113 (Figure 2) of the motors. 35 The other terminal of secondary winding 209 is carried by a conductor 211 down through the insulating terminal 205 and by way of insulating conductor 212 (see also Figure 3) is extended into the tube member 122 where it is connected to the 40 conductors 114 leading respectively to the conductors 113^b (see Figure 2) to the other side of the windings 113. Thus, driving energy is supplied to the two motors.

45 As for details of other aspects of the construction and as for the details of the action and coactions of the various parts, reference is to be made to my above-mentioned co-pending application of which this is a division.

50 As many possible embodiments may be made of the above invention and as many changes might be made in the embodiment above set forth, it is to be understood that all matter hereinbefore set forth, or shown in the accompanying drawings, is to be interpreted as illustrative 55 and not in a limiting sense.

I claim:

1. In an electrical treating apparatus of the type having a support member and a plurality of electrodes, an insulator comprising a segment 60 of a cylinder which segment includes a ring-like portion and loop-shaped portions attached to said ring-like portion at spaced points, said ring-like portion providing means for mounting said electrodes at points upon said ring-like portion intermediate the points at which said loop-shaped portions are attached and said loop-shaped portions being mounted upon said support member so as to insulate and support said electrodes from said support member. 65

2. In an electrical treating apparatus of the type having a support member and a plurality of electrodes, an insulator comprising a segment of a cylinder which segment includes a ring-like portion and loop-shaped portions attached to 70

75

said ring-like portion at spaced points, said ring-like portion providing means for mounting said electrodes at points upon said ring-like portion intermediate the points at which said loop-shaped portions are attached and said loop-shaped portions being mounted upon said support member so as to insulate and support said electrodes from said support member, and rigid reinforcing means extending between the points 10 at which said electrodes are mounted.

3. In electrical treating apparatus a fixed shaft, an electrode rotatably mounted upon said shaft, an electrical motor the stator of which is mounted upon said shaft and the rotor of which 15 is mounted upon said electrode, said electrode comprising a bottom plate having apertures near the periphery thereof and an upper cover member, electrode members removably mounted in said apertures, said electrodes being held in 20 place by said cover member.

4. In electrical treating apparatus a fixed shaft, an electrode rotatably mounted upon said shaft, an electrical motor the stator of which is mounted upon said shaft and the rotor of which 25 is mounted upon said electrode, said electrode comprising a bottom plate having a double row of apertures around said plate near the periphery thereof and an upper cover member, electrode members removably mounted in said 30 apertures, said electrodes being held in place by said cover member.

5. In electrical treating apparatus of the type wherein a product being treated is positioned adjacent an electrode structure within a treatment zone and is subjected to the discharges which result from impressing a high potential upon said electrode structure, in combination electrode means, a main support, a secondary support comprising a stud-like member secured 40 to said main support in juxtaposition to said electrode means, an electrode, means for moving said electrode comprising the stationary and rotary elements of a motor respectively fixedly and rotatably carried by said member, and means 45 for holding a product to be treated in the space between said electrode means and said electrode.

6. An apparatus like that of claim 5 in which the stud-like member is provided with a channel through which driving energy is supplied to the motor.

50 7. An apparatus like that of claim 5 in which the motor is an electric motor and the stud-like member is channeled and carries therethrough conductor means to supply driving energy to the motor.

55 8. In electrical treating apparatus, in combination, a main support, a stud-like member secured to said support, said stud-like member having mounted thereon the stationary element of an electric motor, a housing rotatably supported by said member and having therein the rotating element of the motor, and electrode means carried by said housing.

9. An apparatus like that of claim 8 in which 60 the housing is in two parts, each supported rotatably by said stud member, one above the stationary element and the other below the stationary element.

10. An apparatus like that of claim 8 in which 65 a terminal of the motor is connected to the stud member, the latter being channeled, another terminal of the winding having connected thereto to a contactor leading through the channel in said stud member.

70 11. An apparatus like that of claim 8 in which

means are provided peripherally of the housing for supporting the electrode means.

12. An apparatus like that of claim 8 in which 5 means are provided detachably supporting the electrode means.

13. An apparatus like that of claim 8 in which the housing is in two separable parts between and by which the rotary element of the motor is secured.

14. An apparatus like that of claim 8 in which 10 the housing has a portion extended over the end of said stud member opposite from said support, thereby totally enclosing the motor elements and said stud member excepting for the portion of the latter secured to the support.

15. An apparatus like that of claim 8 in which the housing is in two parts, one part being apertured to have one end of said stud member extend therethrough for securing to said support and the other part extending over the other 20 end of said stud member.

16. An apparatus like that of claim 8 in which the axis of rotation of the electrode means is substantially vertical, the electrode means being shaped to project in the direction of said 25 axis.

17. In an electrical treating apparatus, an electrode for a discharge comprising a movable carrier having openings therethrough for reception of removable electrode members, said electrode members being tilted so that their axes trail from the face of said carrier with respect to the rotation thereof, and electrode members each having a portion adapted to limit the movement of the electrode into the opening, 35 a portion fitted in said opening and a tapered portion substantially within a geometrical figure formed by projection of the cross-sectional shape of the smallest part of the opening along the axis but beyond the end of the opening.

18. In an electrical treating apparatus, an electrode for a discharge comprising a movable carrier having openings therethrough for reception of removable electrode members, said electrode members being tilted so that their axes trail 45 from the face of said carrier with respect to normal rotation thereof, and electrode members each having a head portion adapted to limit the movement of the electrode through said opening, a substantially cylindrical portion fitted in said opening, and a substantially conical portion substantially coaxial with the cylindrical portion.

50 19. In electrical treating apparatus of the type wherein a product being treated is positioned adjacent an electrode structure within a treatment zone and is subjected to the discharges which result from impressing a high potential upon said electrode structure, in combination, a high voltage discharge circuit having spaced means between which discharge takes place, said spaced 55 means including a support, a discharge electrode and means comprising a socket in said support for removably mounting said discharge electrode in said support.

20. In electrical treating apparatus, in combination, a stud-like member having mounted thereon the stationary element of a motive means, a cooperating rotatable element for said motive means, a two-part frame-like means having portions between which said rotatable element is received, means for securing said two parts together and for thereby clamping said rotatable element therebetween, bearing means for rotatably supporting said frame-like means and hence said rotatable element with respect 70 75

to said stud-like member, and electrode means carried by said frame-like means and hence adapted to be rotated upon rotation of said frame-like means relative to said stud-like member.

5 21. In electrical treating apparatus, in combination, a stud-like member having mounted thereon the stationary element of a motive means, a cooperating rotatable element for said motive means, a two-part frame-like means having portions between which said rotatable element is received, means for securing said two parts together and for thereby clamping said rotatable element therebetween, bearing means for 10 rotatably supporting said frame-like means and hence said rotatable element with respect to said stud-like member, the two parts of said frame-like means having juxtaposed portions which are separable when said two parts are separated, and 15 20 electrode means carried by said frame-like means and held in place by said two separable portions.

22. In electrical treating apparatus, in combination, a stud-like member having mounted thereon the stationary element of a motive means, a cooperating rotatable element for said motive means, a two-part frame-like means having portions between which said rotatable element is received, means for securing said two parts together and for thereby clamping said rotatable element therebetween, bearing means for 25 30 rotatably supporting said frame-like means and hence said rotatable element with respect

to said stud-like member, one of said parts of said frame-like means having a socket, and an electrode seated in said socket, the other of said parts of said frame-like means having an extension coaxing with said socket to hold said electrode therein.

23. In electrical treating apparatus, in combination, a stud-like member having secured thereto the stationary element of a motive means, a two-part housing rotatably carried by 10 said stud-like member, said housing having therein the coaxing rotatable element of said motive means, an electrode, one of said parts having seat-forming means in which a portion of said electrode is seated and the other of said 15 parts having a portion coaxing with said seat-forming means to hold said electrode against removal from the latter, and means for holding said two parts together.

24. In treating apparatus of the type wherein 20 a product being treated is positioned adjacent an electrode structure within a treatment zone and is subjected to the discharges which result from impressing a high potential upon said electrode structure, the combination of, a supporting shaft, a motor having stator means mounted upon said shaft and rotor means mounted to move about said stator means, and electrode means mounted to move with said rotor including a hollow shell and a discharge portion having thin metallic walls. 25 30

FRANKLIN S. SMITH.
